UNITED STATES PATENT OFFICE.

ALFRED SMALLWOOD, OF LONDON, ENGLAND.

FURNACE.

1,290,383.

Specification of Letters Patent.

Patented Jan. 7, 1919.

Application filed April 18, 1916. Serial No. 91,943.

To all whom it may concern:

Be it known that I, ALFRED SMALLWOOD, a subject of the Kingdom of Great Britain, residing at 42 Hargrave Park, Highgate, 5 London, N., in the county of Middlesex, England, metallurgist, have invented certain new and useful Improvements in or Relating to Furnaces, of which the following is a specification.

10 This invention relates to furnaces of the type in which the provision for generating the primary heat is in communication with the one end of a combustion chamber, which combustion chamber is in communication 15 at its other end with a space within the floor of the goods chamber, and in such an arrangement the space within the floor of the goods chamber has been in communication with a jacket flue for heating the contents of the goods chamber.

According to the present invention in such an arrangement, a flue or flues are incorporated, which flue or flues are in communication on the one hand with the end 25 of the combustion chamber remote from the provision for generating the primary heat, and are on the other hand in communication at intervals along their length with the interior of the hollow floor of the goods 30 chamber, the several means of communication between the said flue or flues and the interior of the hollow floor being individually regulable.

The furnace gases from the combustion 35 chamber can thus be passed directly or substantially directly to various different parts of the floor, whereby a greater or lesser heat may be imparted to any part of the floor to thereby effect an even or an appropriate 40 heating of the goods chamber.

In order that this invention may be clearly understood and readily carried into practice, reference may be had to the appended explanatory sheet of drawings, upon which:—

45 Figure 1 is a side sectional elevation of a furnace according to the present invention.

Fig. 2 is a sectional end elevation of the furnace shown in Fig. 1, the plane of section being on line 1—2 of Fig. 1.

50 Fig. 3 is a section taken on lines 3, 4, of Fig. 1 and Fig. 4 is a section taken on line 5, 6 of Fig. 1.

In a convenient embodiment of the present invention, the furnace structure takes 55 the form of a building having a solid fuel fire grates *a* or liquid or gaseous fuel fit-

tings incorporated at one extremity and adapted to communicate with an arched combustion chamber *b* extending throughout substantially the entire length of the 60 building. Above the arch of the combustion chamber, there are arranged at suitable points, bricks, upon the upper surface of which bricks the floor *c* of the goods chamber *c*² is disposed so as to leave a space *c*¹. 65 At its outlet extremity *d*, the space *c*¹ above the combustion chamber is placed in suitable communication with flues *e*, *e* in the side walls of the goods chamber. The flues *e*, *e* in the side wall communicate at the rear end 70 of the furnace with the flue *f* or flues in the crown by means of the passage *j*.

The combustion chamber may be in communication with the hollow floor at its extremity remote from the fire-grate or primary combustion end of the furnace, by way of openings *i* and the gases in the combustion chamber are passed into longitudinal flues *g*, *g*, by way of the opening *k* which last-mentioned flues may be disposed 80 below the flues *e*, *e*, and which flues *g*, *g* are in communication with the interior *c*¹ of the hollow floor, by a series of ports *h* arranged at intervals along the length of the furnace, and which ports *h* are individually 85 regulable by means of suitable slabs *h'*, access to which may be had by way of the opening *h''*.

In connection with the present invention I may employ provision according to which 90 the air for combustion is heated by being passed into the vicinity of the furnace gases when they are passing through the jacket flue in the crown of the goods chamber.

Furthermore, I may in the present furnace incorporate provision for passing heated air to the combustible at two points, one of which is the primary point of combustion, the other point of admission of heated air being at a point occurring in the 100 progress of the furnace gases after the primary point of combustion, and conveniently after the combustion chamber has been traversed, in which, in such an arrangement, a part of the combustible gases are not ignited in view of the fact that insufficient air has been admitted at the point of primary ignition. In applying this arrangement to the furnace shown, provision may, for instance, be provided for supplying a limited 110 amount of heated air at the bridge and for supplying further heated air directly to the

space c^1 within the hollow floor of the goods chamber, so that within such floor the combustion of the furnace gases is completed in the direct vicinity of the chamber containing the goods.

What I claim as my invention, and desire to secure by Letters Patent is:—

A furnace including a combustion chamber, a goods chamber arranged above said combustion chamber, a hollow floor provided between the goods and combustion chambers, passages arranged one to each side of said combustion chamber and having one of their ends in communication therewith, such passages being provided with individually regulable ports communicating at their upper

ends with the hollow floor, further passages formed along the end and sides of the goods chamber, the lower portion of the end wall passage communicating with the hollow floor and the upper end thereof communicating with one end of the side wall passages, and a hollow ceiling for said goods chamber, the other end of the side wall passages communicating with one end of said hollow ceiling. 25

In witness whereof I have hereunto set my hand in the presence of two witnesses.

ALFRED SMALLWOOD.

Witnesses:

ARTHUR BROWN,
HOLLIS BROWN.
